WASHING APPARATUS

Leslie A. Kempton, Chicago, Ill., assignor to Edison General Electric Appliance Company, Inc., Chicago, Ill., a corporation of New York

Application August 27, 1937, Serial No. 161,251

11 Claims. (Cl. 141—9)

This invention relates to washing apparatus, more particularly to dishwashing apparatus, and it has for its object the provision of an improved device of this character.

5 This invention has particular application to dishwashing apparatus wherein a cleansing liquid, such as hot water, is circulated in the washing vat through dish-supporting racks by means of suitable power-driven means, such as a motor-driven impeller. In one of its aspects, this invention contemplates the provision of improved means for controlling washing apparatus of the above character including means for automatically supplying the washing vat with a predetermined quantity of cleansing liquid.

More specifically, this invention contemplates improvements in the washing machine control described and claimed in the copending application of Forrest A. Walker and Gustave F. Maisch, 20 Serial No. 86,396, filed June 20, 1936, and assigned to the same assignee as this invention.

For a more complete understanding of this invention, reference should be had to the accompanying drawings in which Fig. 1 is a vertical front elevation of dishwashing apparatus embodying this invention, parts being broken away and parts shown in section so as to illustrate certain details of construction; Fig. 2 is an enlarged fragmentary view in elevation illustrating control apparatus for the washing device of Fig. 1 arranged in accordance with this invention; Figs. 3, 25 4 and 5 are fragmentary views in elevation illustrating a portion of the control apparatus of Fig. 2 in its different operative conditions; Figs. 6, 7 30 and 8 are fragmentary views in elevation illustrating parts of the control apparatus of Fig. 2 in different operative conditions; Figs. 9 and 10 are vertical sectional views taken through the lines 9—9 and 10—10 respectively of Fig. 2 and 35 40 looking in the direction of the arrows; and Fig. 11 is a diagrammatic view illustrating the impeller driving motor and certain control apparatus associated therewith arranged in accordance with this invention.

45 Referring to the drawings, this invention has been shown in one form as applied to household dishwashing apparatus of the front-opening type. Referring more specifically to Fig. 1, this washing apparatus comprises a casing or cabinet 10 enclosing a suitable vat 11. The casing 10 is provided with a front opening 12 whereby access may be had to the vat. This opening is normally closed by a cover 13. Arranged within the vat is a suitable dish-supporting rack 14, which is slidably mounted on suitable rails 15 provided on op-

posite sides of the vat so that when the front door 13 is open, the rack may be moved forwardly for loading and unloading. Arranged in the bottom of the vat below the rack is a suitable water circulating impeller 16. The impeller 16 is driven by an electric motor 17 supported below the bottom wall of the vat and connected to the impeller by means of a shaft 18 extending upwardly into the vat where it is connected with the impeller. The bottom wall of the vat, as shown, is inclined 10 downwardly toward the center where a drain opening 19 is provided.

This opening is controlled by means of a drain valve 20. The drain valve 20 is opened by means of an operating lever 21. When the lever is in its 15 position shown in Fig. 1, the drain valve 20 is open. The lever is held in this position by means of a cable 22 which is tensioned by a spring 23. The flexible cable 22 is guided upwardly through the vat to an operating knob 24. The operating 20 knob 24, as shown in Fig. 1, is accessible on the exterior of the front wall of the cabinet. The operating knob operates a shaft 25 which is mounted in a U-shaped supporting bracket 26. Rigidly secured on the inner end of the shaft 25 is an 25 operating lever 21. The upper end of the cable 22 is secured to one end of the lever 21, as shown, by winding it about a pin 28 secured to the lever and then attaching the extreme end of the cable to a stud 29. The lever 21, as shown, can swing 30 between two positions (Figs. 2 and 7 and 8) defined by the end walls of the bracket 26. In the position of the lever in Fig. 2, the drain valve is opened, whereas when the knob 24 is rotated in a clockwise direction to move the lever to its position of Figs. 7 and 8, the cable is released to permit the drain valve to close. The bracket 26 is rigidly secured to a metallic control panel 29a which in turn is rigidly secured to the upper front portion of the cabinet 10. The cable 22 is 35 40 cased in a housing 29b which is secured by supporting clips 29c.

Cleansing liquid is supplied to the vat from a suitable conduit 30 which is connected with any suitable source of cleansing liquid supply, such as 45 a hot water tank (not shown). This conduit is connected with a conduit 31 which is connected with the vat through a pair of valves 32 and 32a. The water enters the vat through a spray device 33b. The valve 32 is a manually operable valve 50 and is normally in its open position, the control of the water to the vat in the normal operation of the apparatus being solely by the valve 32. The valve 32a is of the self-closing type. That is, when the valve has been opened and is then re- 55

leased, it will automatically move to its closed position. The valve is moved to this position by means of a spring (not shown) which is incorporated in the valve structure.

5 The supply valve 32a is moved to its open position against the force of its spring by means of a manually operable control knob 33 also accessible at the front upper portion of the cabinet 10, as clearly shown in Fig. 1. The knob 33 is keyed to 10 an operating shaft 34 which is mounted on a metallic panel 35. The panel 35 is rigidly secured to the panel 29a in any suitable manner as by screw-fastening means 36. As shown more clearly in Fig. 10, the rear end of the shaft 34 is journaled in the panel 35, whereas its forward end is supported in a U-shaped bracket 37 secured to the panel by means of screw fastening means 37a. Mounted on the rear side of the panel 35 and rigidly secured to the inner end of the shaft 34 is a 15 plate or lever 38. This lever is used to operate the supply valve 32a to its open position when the knob 33 is moved in a clockwise direction. For this purpose, the lever 38 is mechanically connected to the supply valve as follows: Connected 20 with the operating lever of the supply valve 32a is a rod 39 vertically arranged in the cabinet and extending from the valve 32a upwardly to the control panel where it is connected at its upper end with an arm 40 mounted to rotate on the 25 panel 29a by means of a pin or stud 41. Rigidly secured to the arm 40 is a second arm 42 arranged substantially at right angles to the arm 40, as clearly shown in Figs. 2, 6 and 7, the two arms, in effect, constituting a right-angle bell 30 crank pivoted at the angle. The free end of the arm 42 is connected to a slide bar 43. This bar, as shown, is provided with an elongated slot 44 which receives a pin 45 mounted on the panel 29a. A pin 46 is provided on the lever or plate 38 and 35 the parts are so related that when the lever is moved in a clockwise direction, the pin engages the adjacent end of the slide to move the slide to the left from its position of Fig. 6 to its position of Fig. 7. This operation elevates the rod 39 and 40 opens the supply valve 32a. When the plate 38 is moved in a counter-clockwise direction from its position of Fig. 7 to its position of Fig. 6, the inlet 45 valve is permitted to close by means of its spring.

The control knob 33 is also used to control the 50 energization of the impeller driving motor 17, and in addition functions to control suitable means for automatically effecting the closure of the supply valve 32a when a predetermined quantity of water has been supplied to the vat.

55 For the purpose of automatically effecting the closure of the liquid supply valve 32a, the supply valve in the first instance when moved to its open position is latched in this position by means of a latching lever 47 pivotally mounted intermediate 60 its ends on the panel 35 by means of a pin 48. The latching member 47 carries on its right-hand portion, as viewed in Figs. 2, 3, 4, 5 and 8, a latching member or tooth 47a arranged substantially at right angles to the lever and extending through 65 an aperture 49 provided for it in the panel 35. The upper end of the lever 38 is provided with a detent or tooth 50, and the member 47a and the tooth 50 are so related that when the knob 33 has been moved in a clockwise direction a sufficient 70 distance to open the supply valve, the member 47a will engage the tooth to lock the lever in its position shown in Fig. 7, thereby holding the supply valve open against the bias of its closing spring. The latch is biased to its latching position by means of a spring 50a.

The latching lever 47 is movable on its pin 48 in a counter-clockwise direction, as viewed in Figs. 2, 3, 4, 5 and 8, to release the inlet valve by means of an electromagnet 51. The armature 51a of the magnet carries a pin 51b which is extended 5 through an aperture 51c in the lever so that when the excitation or energization of the electromagnet has been increased to a predetermined value, the armature will move the lever to release the supply valve 32a.

The electromagnet is connected in the armature circuit of the impeller driving motor 17 when the inlet valve 32a is opened so that, if under these conditions the drain valve is closed, the water supplied to the vat 11 will accumulate therein; 15 and as the quantity of water in the vat increases, the armature current and excitation of the magnet will increase due to the increasing load imposed on the impeller 16. Eventually upon the occurrence of a predetermined armature current 20 due to a predetermined supply of water in the vat, the electromagnet 51 will operate to release the supply valve to shut off the water.

The energization of the electromagnet 51 is also controlled by means of the control member 33. 25 To control both the motor 17 and the electromagnet, the control member 33 operates a suitable switch 52 comprising a pair of fixed spaced contacts 53 and 54 mounted on an electrically insulating block 55 that is riveted or otherwise rigidly 30 secured to the panel 35. As shown more clearly in Fig. 10, the contact 53 is positioned back of the contact 54. Cooperating with these fixed contacts respectively and positioned in the space between them are a pair of movable switch arms 56 35 and 57, the arm 56 being positioned back of the arm 57, as shown in Fig. 10. The switch arms 56 and 57 are formed of a suitable electrically conducting flexible spring material, and at their lower ends they are rigidly secured to a conducting 40 plate 58 that is also rigidly secured to the electrically insulating block 55. The inner arm 56 is normally biased to its closed position by its inherent resiliency, while the outer switch arm 57 is normally biased to its open position.

The switch arms are controlled by means of a cam 59 rigidly secured to the shaft 34. The cam is formed of a suitable electrically insulating material, such as a phenol condensation product. Also mounted on this shaft is a second controlling 50 cam 60 that functions both as a control cam and also as a positioning cam for the shaft 34. The cam 60, as shown, is provided with a pair of spaced positioning depressions 61 and 62, and with a cam surface 63 the purpose for which will be 55 described in greater detail hereinafter. Cooperating with the positioning depressions is a latch member 64 carrying a detent 64a arranged to be received in them, and also arranged to engage the cam surface 63, as will be described in greater detail hereinafter. The member 64 is pivotally mounted on a pin 65 secured to the panel member 35, and is biased in a clockwise direction, as viewed in Figs. 2, 3, 4 and 5, by means of a spring 66. The depressions are so positioned that the 60 knob is held in its "off" position designated a in Fig. 11, and also in a first controlling position 65 removed from a and designated b.

The electrical connections between the switch 52 and the motor 17 and the electromagnet 51 70 are shown diagrammatically in Fig. 11. As there shown, the motor 17 and magnet are energized from any suitable source of electrical supply 67. As also shown, the electromagnet is connected across the contacts 53 and 54. The lower side of 75

the supply source 17 is connected to the contact 54. The other side of the supply source is connected to one side of the armature circuit of the motor, the other side of which is connected to 5 the two switch arms 56 and 57. This latter connection is effected through the plate 58.

In the operation of the washing apparatus thus far described, it will be understood that when the knob 33 is in its off position *a* the control parts 10 will be as shown in Figs. 2 and 6; the supply valve 32a will be closed, and the motor and electromagnet will be deenergized. If it be desired to wash 15 dishes placed within the rack 14, the drain valve knob 24 will be moved to close the drain valve. Then the control knob 33 will be moved from its off position *a* to its first controlling position *b* 45° away from *a*. In this position, the parts are as 20 shown in Fig. 3. As there shown, the cam 59 is so positioned that it permits the switch arm 56 to remain closed while it positively closes the switch arm 57. This energizes the electric motor 17 and shorts the electromagnet which therefore 25 is deenergized. The motor 17, therefore, will drive the impeller 18. The parts are locked in this position by the detent 64a seating in depression 62. The control member 33 will then be moved 30 to its second controlling position approximately 40° from *b* and indicated *c* in Fig. 11. In this position of the control member, the parts are as 35 shown in Figs. 5 and 7. In this position, the inner contact 53 remains closed, but the outer arm 57 will have been permitted to move to its open position. In this condition of the parts, the electromagnet is connected directly in the armature circuit of the motor 17. Also the movement of the 40 knob 33 to the position *c* will have moved the slide bar 43 sufficiently to open the inlet valve 32a where it is locked by the latching member 47a. Under these conditions, the motor will be operating 45 and water will flow into the vat from the supply source. As the motor load builds up, its armature current also builds and also so does the excitation of the electromagnet 51. Upon the occurrence of a predetermined armature current and, therefore, a predetermined excitation in the magnet 51, the magnet will function to release the inlet valve 32a, in the manner previously described. This automatically measures a predetermined quantity of water for the vat.

50 It will be observed that when the control member 33 is in position *c*, the detent 64a engages the cam surface 63 on the cam 60 (Fig. 5), and that when the latch 47a releases the inlet valve 32a, it releases the shaft 34 and the knob 33 at the 55 same time, whereupon these members are moved back to the first controlling position *b* by the detent 64a acting on the surface. This operation of the shaft 34 disconnects the electromagnet 51 by reclosing the switch arm 57.

60 The apparatus thereafter will function to wash the dishes by the motor operating the impeller to circulate the water in the vat. This operation will continue until the operating knob 33 is manually moved to its off position *a* which returns the parts to their positions shown in Fig. 2 whereon the motor and the electromagnet are both deenergized. The drain valve operating knob 24 may then be returned to its position shown in Fig. 1 to permit the soiled water to 65 drain from the vat.

70 It will be observed that if the operator should grasp the knob 33 while in its off position *a* and rapidly move it through the position *b* to the position *c* wherein the water valve 32a is opened and the motor 17 is energized, there is the dan-

ger that the large inrush of starting current in the motor would energize the electromagnet 51 sufficiently to retract its armature, which operation would, of course, hold the latch in its released position thereby preventing proper functioning of the washing apparatus. To obviate this possibility, I have provided still a third controlling position *d* for the control member 33 (Fig. 11). The parts of the control apparatus in this position are shown in Fig. 4. In this position, the cam 59 is so placed that the switch arms 56 and 57 are in the same positions that they have in the first controlling position *b*, and the electromagnet 51 is short-circuited, while the motor is connected directly to the supply source. 10 If, therefore, the control knob 33 is moved directly to the position *d*, the motor 17 will be energized and will start up, as before, and the fact that it has a large starting current, or that the liquid supply valve 32a is open will have no 15 effect upon the electromagnet 51, because it will be shorted out. The knob 33 is manually held in position *d* against the force of detent 64a acting on cam surface 63, and when released it will be automatically returned to its second controlling position *c* by the detent 64, and it will be held in this position by the latch 47a engaging the tooth 50 in lever 38. The starting inrush of current subsides by the time the operator moves the knob 33 to the position *d* and then 20 releases it to permit it to move to position *c*. Position *d* is positively determined by means of a stop 68 on the panel 35 positioned in the path of downward movement of the arm 64 as shown in Fig. 4. 35

Normally the operator grasping the knob 33 in the off position *a* will move it directly to the position *d* and then releases it. If, however, the operator desires, the knob 33 may be moved, as described previously, first to the position *b* and 40 then to the position *c*.

The inlet valve 32a may be manually released before the automatic release by the electromagnet if it be desired to do so. For this purpose, I prefer to use the valve releasing means described 45 and claimed in the copending application of E. S. Stoddard, Serial No. 161,260, filed August 27, 1937, and assigned to the same assignee as this invention. As there described, a releasing dog 69 is mounted on the inner end of the control shaft 34. The releasing dog 69 is rigidly secured to the shaft, whereas the plate 38 is keyed to the shaft so that it can be rotated freely relatively to the shaft through a few degrees of movement; it will be observed that the key slot 38a 50 provided in the plate 38 is relatively elongated to provide for this limited freedom of movement. The plate 38, and dog 69 are biased to move apart on their axis of rotation by means of a tension spring 70 joining the two members, 55 as shown. It will be noted that when the knob 33 is moved in a clockwise direction to open the supply valve 32a, as previously described, the plate 38 and the dog 69 will move together as a unit, as shown in Fig. 6, the dog leading the upper end of the plate 38 until the latch 47a engages the tooth 50 in the plate 38 to lock it, as shown in Fig. 7. Now if the knob 33 be reversed to move in a counter-clockwise direction, it will move the dog 69 in the same direction independently of the member 38 to engage and release the latch 47a, whereupon the dog and plate 38 will return to their initial positions shown in Fig. 6. 65

If it be desired to rinse the dishes, the drain valve is left open, and the control member 33 is 70 75

moved to position *c*. This permits water to flow into the vat through the spray *33b* continuously until the inlet valve is released by reversing the movement of knob *33*, as previously described.

5 While I have shown a particular embodiment of my invention, it will be understood, of course, that I do not wish to be limited thereto since many modifications may be made, and I, therefore, contemplate by the appended claims to 10 cover any such modifications as fall within the true spirit and scope of my invention.

What I claim as new and desire to secure by Letters Patent of the United States is:—

1. Washing apparatus comprising a vat, means 15 for circulating liquid in the vat, an electric motor for operating said circulating means, a liquid supply valve controlling the flow of liquid to said vat, means operated responsively to an electrical condition in the armature circuit of said motor 20 that varies as the load on said motor varies for controlling the operation of said valve to shut off the supply of liquid when said load attains a pre-determined magnitude, a control member for said last-named means and said motor movable from 25 an off position to one position to effect the operation of said motor and to render said means responsive to said electrical condition, and to a second position in which said motor only operates, and means biasing said control member from said 30 second to said first position so that when the operator releases said control member in the second position, it automatically moves to the first position, the movement of the control member from the off to the second position and subsequently when released to the first position permitting the starting current of the motor to rise 35 and subsequently subside before said responsive means is rendered effective to said electrical condition.

40 2. A dishwashing machine comprising a vat, means in said vat for engaging liquid therein so as to circulate it in the vat, a motor for operating said liquid circulating means, a source of liquid supply for said vat, electroresponsive means 45 controlling said source of liquid supply arranged to be connected to the armature circuit of said motor to respond to the armature current thereof so as to shut off the flow of liquid to said vat when the armature current attains a predetermined magnitude, a switch controlling said electroresponsive means and said motor movable from 50 an off position to a first controlling position wherein said motor is energized, to a second position in which said motor is energized and said electroresponsive means is connected in the armature circuit of said motor, and to a third position in which the motor only is energized, and means biasing said switch from said third to said 55 second position so that when the switch is released in the third position it moves automatically to the second position, the movement of the switch from the off to the third position and subsequently when released to the second position permitting the starting current of said motor to rise 60 and subsequently subside before said electroresponsive means is connected in said armature circuit.

70 3. Washing apparatus comprising a vat, an impeller for circulating liquid in said vat, a motor for driving said impeller, a liquid supply valve for said vat biased to its closed position, a control member for moving said valve to its open position, a latch for locking said valve in said open position, an electromagnetic device arranged to release 75 said latch to permit said valve to close,

means operated by said control member when moved to its position to open said valve to energize said motor to drive said impeller, and to connect said electromagnet in the armature circuit of said motor so that when the armature current builds up to a predetermined magnitude the electromagnetic device is energized to release said latch, and said means operated by said control member when moved to another position to disconnect said electromagnet from the armature circuit of said motor while still leaving the motor energized, and a spring biasing said control member to move from said last to the first-named controlling position, the movement of the control member to said other position and when released to said first-named position permitting the armature current of said motor to rise and subsequently subside before said electromagnetic device is connected in said armature circuit. 5

4. Washing apparatus comprising a vat, a 20 liquid supply valve for said vat biased to its closed position, a liquid circulating device in the vat, a motor for driving said circulating device, a control member for the liquid supply valve to move it to its open position, a latch for holding said 25 supply valve in its open position, an electromagnet arranged to operate said latch to release said valve when energized to a predetermined degree, a switch controlled by said control member comprising a pair of fixed contacts and a pair 30 of movable contacts cooperating therewith arranged when the control member is moved from the off to a controlling position to close both of said contacts, when moved to a second controlling position to open one of said contacts, and to still a 35 third controlling position to reclose said open contact, means biasing the control member to move from the third to the second controlling position, and electrical connections between said fixed and movable contacts and said motor and electromagnetic device arranged so that when said switch is in said first and third controlling positions said electromagnet is cut out of the armature circuit of said motor, and in said second position it is connected in the armature circuit of 40 said motor so that when the armature current builds up to a predetermined magnitude the electromagnet is energized to operate the latch to release the valve, and means operated by said control member when moved from the first to the 45 second controlling positions to open said supply valve, the starting current of the motor building up and subsiding while the control members is successively moved comparatively slowly to the first and second controlling positions before the electromagnet is connected in said armature circuit, and also, the starting current building up and subsiding before the electromagnet is connected in the armature circuit while the control member is moved directly to said third position 50 and subsequently to the second position when released. 55

5. Washing apparatus comprising a vat, a liquid supply valve for said vat biased to its closed position, a device for circulating liquid in said vat, a motor for driving said circulating device, means for holding said supply valve in its open position, an electromagnet arranged when energized to a predetermined degree to effect the release of said holding means to permit said supply valve to close, a control member for said supply valve and motor, switching means controlling said motor and said electromagnetic device comprising movable contacts, and can means operated by said control member arranged to operate said contacts 60 65 70 75

so that when said control member is moved from an off to a first controlling position said motor is energized and said electromagnet is de-energized, when moved in the same direction from said first to a second controlling position said 5 motor is energized and said electromagnet is connected in its armature circuit so that the excitation of said electromagnet varies with the armature current of said motor, means operated by said control member when moved from the first 10 to the second controlling position to open said supply valve, the starting current of the motor building up and subsiding before the electromagnetic device is connected in the armature circuit of said motor when the control member 15 is moved comparatively slowly from the off to the second controlling position, a cam operated by said control member having a pair of depressions corresponding to said off and said first controlling positions and a detent biased to move into 20 said depressions to hold said control member in said positions respectively, said cam also having a surface engaging said detent yieldingly to resist continued movement of said control member in said direction from the second controlling 25 position to a third controlling position wherein said motor only is energized but permitting it to be moved to said third position, a stop engaging said detent to limit movement thereof by said cam and thereby define the third controlling 30 position, said starting current also building up and subsiding before the electromagnetic device is connected in said armature circuit while the control member is moved from the off position directly to the third controlling position and released for return movement to said second controlling position.

6. Washing apparatus comprising a vat, a liquid supply valve for said vat biased to its closed position, means for circulating liquid in said vat, a motor for driving said circulating means, a control member for said motor and supply valve arranged when moved to a controlling position to energize said motor and when moved to a second controlling position to open said supply valve while the motor is energized, a latch for locking said control member in said second controlling position and the valve in its open position, an electromagnet for releasing said latch when excited to a predetermined degree to permit 40 said valve to close, the control member functioning to connect the electromagnet in the armature circuit of said motor in its second controlling position so that when the armature current builds up to a predetermined magnitude the electromagnet is energized to release said latch, and means biasing said control member from said second to said first controlling position so that when said latch is released said control member automatically moves to said first controlling position, the control member in this position functioning to disconnect the electromagnet from the armature circuit of said motor.

7. Washing apparatus comprising a vat, a liquid supply valve for said vat biased to its closed 45 position, means for circulating liquid in said vat, a motor for driving said circulating means, a control member for said motor and supply valve arranged when moved to a controlling position to energize said motor and when moved to a second controlling position to open said supply valve while the motor is energized, a latch for locking said control member in said second controlling position and the valve in its open position, an electromagnet for releasing said latch when ex- 50

cited to a predetermined degree to permit said valve to close, the control member functioning to connect the electromagnet in the armature circuit of said motor in its second controlling position, a cam connected to said control member, means acting on said cam to bias the control member from said second to said first controlling position so that when said latch is released said control member automatically moves to said first controlling position, the control member in 10 this position functioning to disconnect the electromagnet from the armature circuit of said motor.

8. Washing apparatus comprising a vat, a liquid supply valve for said vat biased to its closed 15 position, means for circulating liquid in the vat, a motor for driving said liquid circulating means, a control member movable from an off to a pair of controlling positions, arranged when moved to the second controlling position to open said supply valve, a latch for locking said supply valve in its open position and also for holding said control member in said second controlling position, an electromagnet arranged to release said latch when energized to a predetermined degree, switching 20 means operated by said control member so that when said control member is moved from its off to the first controlling position, the motor is energized and the electromagnet is deenergized and when moved to said second controlling position wherein the liquid supply valve is opened the motor is 25 energized and the electromagnet is connected in the armature circuit of the motor, and means biasing said control member to move from the second to the first controlling position so that when the electromagnet operates to release the latch the control member automatically moves to disconnect the electromagnet from the armature circuit of the motor.

9. Dishwashing apparatus comprising a vat, a liquid supply valve for said vat biased to its closed position, means for circulating water in said vat, a motor for driving said liquid circulating means, a latch arranged to hold the liquid supply valve in its open position, an electromagnet arranged when energized to a predetermined degree to release said latch to permit the supply valve to close, and control means for the motor, supply valve and electromagnet comprising a single control member, switching means operated by said control member arranged when the control member is moved in a predetermined direction from its off position to a first controlling position to energize said motor, and when moved to a second controlling position to energize the motor and connect the electromagnet in the armature circuit of the motor, means operated by the control member when moved to the second controlling position to open the supply valve, a latch member operated by said control member arranged to engage said latch in said second controlling position to hold said control member in said second controlling position and to hold the supply valve open, and means biasing the control member from the second to the first controlling position so that when said electromagnet functions to release said latch the control member automatically moves to the first controlling position to disconnect the electromagnet from the armature circuit of the motor, and means operative to release said latch independently of the operation of said electromagnet when said control member is manually moved from the second to the first controlling position.

10. Washing apparatus comprising a vat, a

liquid supply valve for said vat biased to its closed position, means for circulating liquid in the vat, a motor for driving said liquid circulating means, a control member movable from an off to three controlling positions, arranged when moved to the second controlling position to open said supply valve, a latch for locking said supply valve in its open position and also for holding said control member in said second controlling position, an electromagnet arranged to release said latch when energized to a predetermined degree, switching means operated by said control member so that when said control member is moved from its off to the first controlling position, the motor is energized and the electromagnet is deenergized and when moved to said second controlling position wherein the liquid supply valve is opened the motor is energized and the electromagnet is connected in the armature circuit of the motor, the starting armature current of the motor rising and subsiding before the electromagnet is connected in the armature circuit when the control member is moved comparatively slowly from the off to the first and then to the second controlling position, means biasing said control member to move from the second to the first controlling position so that when the electromagnet operates to release the latch the control member automatically moves to disconnect the electromagnet from the armature circuit of the motor, and means controlled by the control member when moved from the second to the third controlling position for disconnecting the electromagnet from the armature circuit, the biasing means returning the control member from the third to the second controlling position when the member is released, the movement of the control member from the off to the third position and subsequently when released to the second position permitting the starting armature current of the motor to rise and subsequently subside before the electromagnet is connected in the armature circuit.

11. Washing apparatus comprising a vat, means for circulating liquid in the vat, a motor

for driving said circulating means, a liquid supply valve for the vat biased to its closed position, a control member for the liquid supply valve and motor movable from an off to three controlling positions, switching means operated by the control member to energize said motor when the control member is moved to said first controlling position, resilient means holding said control member in said position, means operated by the control member when moved from the first to the second controlling positions for opening said supply valve, a latch for holding said valve in its open position and said control member in said second position, an electromagnet for releasing said latch when excited to a predetermined degree, said switching means connecting the electromagnet in the armature circuit of the motor when the control member is moved to the second controlling position so that the electromagnet is excited in accordance with the armature current of the motor and releases the latch when said current attains a predetermined magnitude, the starting armature current of the motor building up and subsequently subsiding before the electromagnet is connected in the armature circuit when the control member is moved comparatively slowly from the off to the first and then to the second controlling position and the switching means disconnecting said electromagnet when the control member is moved from the second to the third controlling position so that when the control member is moved directly to the third controlling position from the off position said starting armature current is given an opportunity to rise and subside with the electromagnet disconnected and means biasing the control member to move from the third toward the first controlling position, so that when it is manually released in the third controlling position it moves automatically to the second where it is latched, and when released in the second by the electromagnet, it moves automatically to the first where it is held by the resilient holding means.

LESLIE A. KEMPTON. 45

CERTIFICATE OF CORRECTION.

Patent No. 2,142,902.

January 3, 1939.

LESLIE A. KEMPTON.

It is hereby certified that error appears in the printed specification of the above numbered patent requiring correction as follows: Page 3, second column, line 38, for "releases" read release; page 4, second column, line 53, claim 4, for "members" read member; line 74, claim 5, for "can" read cam; and that the said Letters Patent should be read with this correction therein that the same may conform to the record of the case in the Patent Office.

Signed and sealed this 14th day of March, A. D. 1939.

liquid supply valve for said vat biased to its closed position, means for circulating liquid in the vat, a motor for driving said liquid circulating means, a control member movable from an off to three controlling positions, arranged when moved to the second controlling position to open said supply valve, a latch for locking said supply valve in its open position and also for holding said control member in said second controlling position, an electromagnet arranged to release said latch when energized to a predetermined degree, switching means operated by said control member so that when said control member is moved from its off to the first controlling position, the motor is energized and the electromagnet is deenergized and when moved to said second controlling position wherein the liquid supply valve is opened the motor is energized and the electromagnet is connected in the armature circuit of the motor, the starting armature current of the motor rising and subsiding before the electromagnet is connected in the armature circuit when the control member is moved comparatively slowly from the off to the first and then to the second controlling position, means biasing said control member to move from the second to the first controlling position so that when the electromagnet operates to release the latch the control member automatically moves to disconnect the electromagnet from the armature circuit of the motor, and means controlled by the control member when moved from the second to the third controlling position for disconnecting the electromagnet from the armature circuit, the biasing means returning the control member from the third to the second controlling position when the member is released, the movement of the control member from the off to the third position and subsequently when released to the second position permitting the starting armature current of the motor to rise and subsequently subside before the electromagnet is connected in the armature circuit.

11. Washing apparatus comprising a vat, means for circulating liquid in the vat, a motor for driving said circulating means, a liquid supply valve for the vat biased to its closed position, a control member for the liquid supply valve and motor movable from an off to three controlling positions, switching means operated by the control member to energize said motor when the control member is moved to said first controlling position, resilient means holding said control member in said position, means operated by the control member when moved from the first to the second controlling positions for opening said supply valve, a latch for holding said valve in its open position and said control member in said second position, an electromagnet for releasing said latch when excited to a predetermined degree, said switching means connecting the electromagnet in the armature circuit of the motor when the control member is moved to the second controlling position so that the electromagnet is excited in accordance with the armature current of the motor and releases the latch when said current attains a predetermined magnitude, the starting armature current of the motor building up and subsequently subsiding before the electromagnet is connected in the armature circuit when the control member is moved comparatively slowly from the off to the first and then to the second controlling position and the switching means disconnecting said electromagnet when the control member is moved from the second to the third controlling position so that when the control member is moved directly to the third controlling position from the off position said starting armature current is given an opportunity to rise and subside with the electromagnet disconnected and means biasing the control member to move from the third toward the first controlling position, so that when it is manually released in the third controlling position it moves automatically to the second where it is latched, and when released in the second by the electromagnet, it moves automatically to the first where it is held by the resilient holding means.

12. Washing apparatus comprising a vat, means for circulating liquid in the vat, a motor
